UNITED STATES PATENT OFFICE.

HENRY TERSTEGGE AND ROMANUS H. GOHMANN, OF NEW ALBANY,
INDIANA.

OPEN-FRONT STOVE.

SPECIFICATION forming part of Letters Patent No. 389,612, dated September 18, 1888.

Application filed October 14, 1887. Serial No. 252,291. (No model.)

To all whom it may concern:

Be it known that we, HENRY TERSTEGGE and ROMANUS H. GOHMANN, citizens of the United States, residing at New Albany, in the 5 county of Floyd and State of Indiana, have invented certain new and useful Improvements in Open-Front Stoves; and we do hereby declare that the following is a full, clear, and exact description of the invention, which will enable others skilled in the art to which it appertains to make and use the same.

Our invention relates to improvements in open stoves; and it consists in the novel construction of a swinging hearth-fender, foot-rail, check-damper, and other parts, as hereinafter described, and more fully pointed out in the claims.

In the accompanying drawings, Figure 1 is a front elevation of the stove with the blower, 20 check-damper, and side doors in closed position. Fig. 2 is a front elevation of the lower portion of the stove, showing it fully opened and exposing the grate. Fig. 3 is a side and half-plan view of the lower portion of the 25 stove, looking from the right. Fig. 4 is a front elevation corresponding to Fig. 2 and showing the hearth-fender and its attachments swung partly open. Fig. 5 is a detail of one 30 of the side doors or wings. Fig. 6 is a detail of the foot-rail. Fig. 7 is a detail of the check-damper, shown in full lines as when raised and in dotted lines as when lowered on the 35 hearth-fender. Fig. 8 is a bottom view of the hearth-fender, looking from the front, with the rail removed. Fig. 9 is a bottom view of a section of the hearth-fender, showing the curved notches in which the check-damper is supported.

In the drawings, A represents the blower, 40 which is supported by balance-weights inside and adapted to slide vertically and be held in any desired position, as now common in this class of stoves.

B is a swinging hearth-fender provided with 45 a stud, b, at its left-hand inner corner, on which it pivots and swings to and from the stove. This fender is shaped as seen in Figs. 1, 2, 3, 4, and 8, with its front and side faces, b' b², inclined inwardly and downwardly to 50 such an extent that coal, cinders, and the like that may fall thereon will not ordinary

rily rest on said fender, but roll or slide into the ash-pan beneath. This peculiarity of construction is heightened and enlarged by the foot-rail C, which is sprung upon the outer 55 edge of the hearth-fender, and has lugs c engaging openings b³ on said plate to more securely fasten the said rail thereon. The inclined inner facing of the foot-rail is flush with the inclined surface b' b² of the hearth-fender, 6c which materially widens and deepens the receptacle for coal and ashes and renders it impossible for live coal that may drop from the grate to fall upon the floor. The foot-rail is thus made to serve a double purpose, and the 65 pit in the hearth-fender is so materially extended thereby that all danger from an open-grate fire is practically removed. A slight groove, b⁴, is formed along the edge of the hearth-fender, in which the slightly-beveled 70 edge of the foot-rail rests, and this with the lugs on said rail and the corresponding openings in the hearth-fender into which the lugs are sprung makes the foot-rail self-mounting and avoids the necessity of bolts, screws, or 75 other separate means of fastening.

D is a check-damper, attached to the hearth-fender by arms d, which rest in notches b⁵ on the under side of the hearth-fender, a handle, d', at one side, extending outside of the hearth-fender, serving to control the position of said 80 check-damper. This damper, like the foot-rail, is self mounting, and requires no bolts or other extra means to hold it in position. When the hearth-fender is in position for use and the 85 check-damper is raised, it turns in its bearings and rests on the base-plate of the stove. When the hearth-fender is swung open, the check-damper is first lowered into the depression b⁶, formed in the hearth-fender for that purpose. 90 It cannot then be displaced or removed without raising it sufficiently to release its arms from the notches b⁵, and removal can only occur when the hearth-fender is open.

The check-damper D is designed to close 95 the lower front part of the stove, thereby checking the draft, and also preventing fire and ashes from falling anywhere except in the ash-pan; but it also can be used to throw off into the ash-pan any ashes or cinders that may 100 accumulate on its surface when it is down.

It will be observed that the grate stands

out some distance from the front of the stove. This exposes the sides of the grate, as at F, to the outer air and renders necessary means to close the same. For this purpose we employ side doors, G, which slide in grooves g' on the base-plate and through vertical slots or openings g^2 in the front plate of the stove. The side doors and the check-dampers make close connection at their meeting edges, and thus together serve to effectually cut off the draft and close the lower part of the stove. When the check-damper is down on the hearth-fender, the entire fender, with the foot-rail, can be swung out of the way for the purpose of taking out the ash-pan, which is then within reach, and there are no loose pieces whatever about the structure, as there usually are about open stoves, most of them having a loose piece with a handle, which is removed and placed on the floor, and when hot is liable to burn the hands and the carpet or floor as well.

We do not wish to confine ourselves to the exact details herein described as connected with the several parts of the invention, as obviously there might be mechanical changes made in the structure without departing from the spirit of the invention.

It will be observed from the foregoing description that we have in addition to the usual hearth or bottom of the stove a supplemental hearth in our swinging hearth-fender—that is to say, the swinging fender, while it serves all the purposes of an extended hearth or stove-bottom, performs the new and valuable function of a perfect fender for the stove, thus making an open-grate fire in a stove absolutely safe and allowing nothing whatever to come from the fire and reach the floor, the fender by the peculiarity of its construction preventing such escape and the accidents and losses liable to flow therefrom.

Having thus described our invention, what we claim as new, and desire to secure by Letters Patent, is—

1. In combination with a stove having a grate, a swinging hearth-fender and a check-damper pivotally connected with said hearth-fender and constructed to be turned up in front of the grate, substantially as set forth.

2. In combination with a stove having a grate, a horizontally-swinging hearth-fender, and a check-damper attached thereto along its inner edge on pivots with handle to operate same at one end, whereby the said check-damper may swing away from the stove with the hearth-fender and be operated substantially as set forth.

3. In a stove, a swinging hearth-fender having inwardly and downwardly inclined sides, in combination with a foot-rail secured upon the edge thereof flush with its surface, forming a hearth-fender, substantially as set forth.

4. In a stove, a swinging hearth-fender having inwardly and downwardly inclined sides, in combination with a foot-rail sprung upon the said fender and having its inner face inclined to correspond to the inclined surface thereof, forming a hearth-fender, substantially as set forth.

5. In combination with a stove, a swinging hearth-fender and a check-damper and foot-rail attached to said fender and swinging therewith, substantially as set forth.

6. A stove having a projecting grate, in combination with side doors to close the ends of the grate and a swinging hearth-fender having the check-damper attached thereto and adapted to be raised and to close the front of the grate, substantially as set forth.

7. In a stove provided with a grate, a draft-plate pivoted to be raised and close the front of the grate and sliding doors to close the ends of the same, substantially as set forth.

8. In a stove provided with a grate, a hearth-plate with foot-rail attached, forming a hearth-fender, and said hearth-fender provided with a check-damper pivoted to be raised to close the front of the grate, substantially as set forth.

In testimony whereof witness our hands this 6th day of October, 1887.

HENRY TERSTEGGE.
ROMANUS H. GOHMANN.
